Be it known to all men that we, Boston Darling and Benjamin Darling, Bellingham, Mass.,

Letters Patent

The Undersigned, to invent the Little Patent and making part of the same containing
a description in the words of the Little Patent, Boston Darling and Benjamin Darling, Mass.,
the inventors of this "invention, my, and their true name."

No all to whom these presents shall come. Be it known that we, Boston Darling and Benjamin Darling, both of Bellingham in the County of Norfolk and State of Massachusetts, have invented a new and useful improvement in the construction of Pistols, and shot guns, and that the following is a full and exact description of said improvement, and of the construction and operation of the said Pistol and Gun, as invented and improved by us. To, we call the same "the rotary Pistol" and as it consists of two barrels or barrels united, cut out of a single piece of steel, placed in a circle parallel with each other, and surrounding a common center or bar which center is for the reception of an iron axle around which the barrels are to revolve. One end of this axle is fastened into the stock of the gun at the breach of the barrels and the end at the mouth of the barrels is fitted for the reception of a screw. This screw screws into the axle in a direction parallel to its axis, and the screw prevents the barrels from slipping off from the axle. The lock of the Pistol is in common form containing a mainspring, a dog and trigger for moving a common hammer or hammer or cork. This is placed on the axle before mentioned, a rotating flat ring or Washer between the breach of the barrels and the stock. On the side of this ring towards the barrels is fixed a small cog or spring which is fitted to play into notches cut into the bar which is in a direction parallel with the axis of the axle in the manner of a cog wheel. Then an end of this cog is in the breach, one for each barrel. To the end of this ring next to the stock, is attached a small bar or ring or a pin or fulcrum, placed at a suitable distance from the breach. This bar is moved by a hand or string fastened to the hammer, and instead of the flat ring or washer, a spring hook is attached to the end of the bar. By drawing back the hammer to a point the bar is depressed and the forward ring with its cog is moved on the axle from left to right and comes toward the barrels, bringing the nippes of the barrel directly over the hammer. The motion of the hammer is striking the nippes and cap, raising the barrel, carrying back the ring and cog far enough to catch into the next notch. By drawing back the hammer the first motion is repeated, and so on till each nippes of each barrel is depressed.

bougle under the hammer for discharge. Each barrel has its separate nipple at the breech and the barrels of said Pistol are charged for firing in the usual manner of other firearms. The machine work of the Pistol and lock is concealed within the stock except the hammer above and the trigger and nipple below the same. The stock of the Pistol may be made of malleable cast iron, common wrought iron or other malleable metal.

What I claim as our own invention and not previously known in the above described Pistol is the division of the barrel in a single piece of steel as described above, also the rotary motion as mentioned in the specification and applied to the barrels of the said Pistol and also the making of the stock of said Pistol of malleable cast iron or wrought iron or other malleable metal.
